LIQUID STORAGE TANK

Walter C. Klank, Jr., Dayton, Ohio, assignor to United Aircraft Products, Inc., Dayton, Ohio, a corporation of Ohio

Filed May 21, 1959, Ser. No. 814,885

6 Claims. (Cl. 137—43)

This invention relates to tanks storing a liquid and useful in vehicles such as aircraft wherein the tank assumes varying attitudes relative to the earth's surface in correspondence with the movements of the aircraft. While not so limited, the invention has especial application to oil supply systems in aircraft wherein an oil is taken from the tank to a place of use and then returned to the tank for storage and subsequent reuse.

In tanks and systems as described, the oil returning to the tank is accompanied by relatively large amounts of air. It is a design objective to provide for the rapid and efficient release of such air from the tank.

A general object of the invention is to provide a new vent system in a tank as described particularly characterized by means restricting the escape of liquid from the tank by way of the vent system in and during movement to changing tank attitudes, including a roll.

Another object of the invention is to present a new vent valve for use in tanks as described characterized by means restricting an escape of liquid through the vent system not only in inverted flight and under conditions of negative gravity but also in a roll attitude of predetermined direction and extent.

Other objects and structural details of the invention will appear from the following description when read in connection with the accompanying drawings, wherein:

Fig. 1 is a diagram of a tank having a vent system in accordance with the illustrated embodiment of the invention;

Fig. 2 is a view, partly diagrammatic, showing a dual valve comprised in the vent system as it appears in a level flight attitude;

Fig. 3 is a view like Fig. 2 showing the valve as it appears in a 90° roll flight attitude, the roll being in a counterclockwise direction from level attitude;

Fig. 4 is a view like Figs. 2 and 3 showing the valve as it appears under conditions of negative gravity, the valve also assuming this position in inverted flight; and

Fig. 5 is a view like Figs. 2 to 4 showing the valve as it appears in a clockwise direction 90° roll.

Referring to the drawings, the tank and the liquid and vent systems associated therewith are shown in the main in diagrammatic form, the invention having particular reference as noted to a dual valve mechanism in the vent system and to the manner in which such valve affects venting in the tank.

Thus, a liquid storage tank in accordance with the illustrated embodiment of the invention comprises a tank shell 10 having a liquid inlet 11, a liquid outlet 12 and a vent or air outlet 13. The liquid inlet is, in tanks of the present class, selectively located and arranged in cooperation with other elements of the tank to admit the returning liquid to the tank in a manner to promote the release of entrained air and to avoid turbulence. In the present instance, the returning liquid is admitted to the lower end of a compartment 14 within the tank. The mixture of liquid and air rises in the compartment 14 and spills out over the open upper end thereof, the period of

2

containment within the compartment providing a dwell period in which the air tends effectively to separate from the liquid. Upon discharge over the upper end of the compartment, therefore, the liquid spills over the upper edge into the main body of contained liquid while the air continues to rise, moving into the upper part of the tank above the liquid level. The liquid outlet 12 may be suitably located for discharge of the liquid and in some instances is associated with means to insure a continuing supply of liquid in different flight attitudes. In the present instance the location of the outlet 12 is in what may be considered to be the normal lower portion of the tank in that its location is at the bottom of the tank when the tank is in a normal, level, flight attitude. It is thus continuously supplied with liquid in most flight attitudes.

The vent outlet 13 is in the normal upper portion of the tank, having regard to normal flight attitudes. The outlet 13 is a part of a vent system further including a chamber 15 which communicates with the outlet 13 and is defined by a wall 16 serving essentially to exclude the chamber 15 from communication with the main interior of the tank 10. Communicating freely with the vent chamber 15 is one end of a tube 17 extending toward the lower part of the tank shell and communicating therewith at its opposite end. Other tubes 18 and 19 are disposed within the vent chamber 15 and have their one ends opening through the wall 16 to communicate with the interior of the tank in the upper portion thereof at opposite ends of the vent chamber, as indicated. At their opposite ends the tubes 18 and 19 communicate with the interior of the vent chamber 15 through a valve 21 in a manner to be more particularly described. The several tubes 17, 18 and 19 are formed in circuitous fashion to obviate the entrapment of liquid therein as the tank moves from one attitude to another and the consequent "slugging" or discharge of the trapped oil into the vent chamber 15. Such liquid as may be admitted to the vent chamber may escape therefrom, however, by way of the tube 17 when the tank returns to a normal flight attitude. The venting arrangement, it will be understood, is one to vent the interior of the tank in varying tank attitudes and under varying conditions. The tubes 18 and 19 vent the upper portion of the tank continuously in normal flight attitudes and in longitudinally tilted positions corresponding to climbing and diving attitudes. Tube 17 vents the tank under inverted flight conditions and inverted like conditions wherein the contained liquid moves to the normal upper part of the tank in response to the application of negative gravity forces, or to inverted flight.

Referring now to Figs. 2 to 5, the valve 21 includes a fabricated body 22 wherein a transverse partition 23 divides the interior of the body essentially into compartments 24 and 25. In what may be considered to be the upper surface of the body 22 is an opening 26 communicating the compartment 25 with the chamber 15. The sides of the valve body are adapted, in a manner not fully shown herein, to receive the adjacent ends of the tubes 18 and 19, the latter being disposed to communicate with body chamber 24. An opening 27 in the partition wall 23 intercommunicates the compartments 24 and 25. Within the compartment 24 is a frusto-conical cage 28, the frustum thereof terminating in the wall 23 in surrounding relation to the opening 27. There is similarly provided in the compartment 25 a frusto-conical cage 29 terminating at its frustum in the upper wall of body 22 in surrounding relation to the opening 26. The arrangement is one to place the cages 28 and 29 at right angles to one another. In a normal, level flight attitude, illustrated in Fig. 2, the cage 28 is hori-

zontally disposed while the cage 29 is vertically disposed. Within the cages are respective freely rolling balls 31 and 32 of a size to seat in and close the respective openings 27 and 26.

As shown in Fig. 2, in a normal flight attitude the balls 31 and 32 both occupy positions removed from the openings 26 and 27. Ball 32, under the influence of gravity, lies in the bottom or base of the cage 29. Ball 31, under the combined influences of gravity and the inclination of the side wall of cage 28, lies also at the bottom of the cage and in a position of rest on the side wall thereof. Under these conditions, therefore, a free movement of air from the tubes 18 and 19 to the vent chamber by way of compartment 24, opening 27, compartment 25 and opening 26 is permitted. In the event of a 90° roll to the left or in a counter-clockwise direction, however, the ball 31 rides up the wall of the cage 28 and comes to rest within the opening 27, effectively closing such opening. The compartment 24 is thereby cut off from communication with the compartment 25 so that the tubes 18 and 19 are disconnected from the vent chamber 15. Liquid which might enter the vent chamber under these conditions by virtue of flooding of the outer open ends of the tubes 18 and 19 accordingly is denied entrance. Ball 32 remains in the bottom of the cage resting against one side wall thereof.

Fig. 4 illustrates the position of the balls 31 and 32 under the influence of negative gravity forces or in an inverted flight attitude. Under the conditions then applying the ball 32 moves to the frustum of the cage 29 and seats in opening 26. Communication of the tubes 18 and 19 with the vent chamber 15 thus is precluded as in the roll attitude of Fig. 3. Fig. 5 illustrates the 90° roll in the opposite direction wherein as seen no interruption of communication between the tubes 18 and 19 and the vent chamber 15 is contemplated. It will be understood, however, that communication could under these conditions be discontinued also if desired, as by interposing between the cages 28 and 29 a further cage and ball, the cage being aligned with the cage 28 but inversely arranged.

Figs. 2 through 5 are, as heretofore noted, partly diagrammatic. The diagrammatic manner of execution is directed primarily toward a clear showing of the manner in which compartment 24 of valve assembly 21 communicates with adjacent ends of pipes 18 and 19. True vertical longitudinal sections through the valve assembly would remove one of the pipes 18 or 19 from view entirely and would partly obscure the other by reason of the presence of ball 31. Accordingly, for purposes of clarity and simplicity, in Figs. 2 through 5 the pipes 18 and 19 have been in effect rotated some 90 degrees about the body 22 so that in vertical sectional views as used both pipes are visible.

What is claimed is:

1. A liquid storage tank which in use assumes different attitudes relative to the earth's surface and which includes outlet and inlet connections, the latter admitting to the tank a liquid-air mixture; including a vent line to pass admitted air out of the tank from the normal upper portion thereof; and a pair of normally open gravity operated valves in said vent line, one closing said line under conditions of inverted tank attitude and under conditions of negative gravity, and the other closing said line under conditions of a roll attitude of predetermined direction and extent.

2. A liquid storage tank which in use assumes different attitudes relative to the earth's surface and which includes outlet and inlet connections, the latter admitting to the tank a liquid-air mixture; including a vent line to pass admitted air out of the tank from the normal upper portion thereof; and a pair of normally open gravity operated valves in said vent line, one closing said line under conditions of inverted tank attitude and

under conditions of negative gravity, and the other closing said line under conditions of a roll attitude of predetermined direction and extent.

3. A liquid storage tank which in use assumes different attitudes relative to the earth's surface and which includes outlet and inlet connections, the latter admitting to the tank a liquid-air mixture; including a vent chamber in said tank communicating with the tank exterior; vent tubes communicating at their one ends with different portions of the tank interior and terminating at their opposite ends in said vent chamber, at least one of said vent tubes communicating at its said one end with the normal upper portion of the tank interior; and valve means controlling the communication of said one tube with said vent chamber, said means closing said tube from communication with the vent chamber under conditions of inverted tank attitude and under conditions of negative gravity and also under conditions of a roll attitude of predetermined direction and extent, said valve means comprising a pair of independently operable series arranged valves, one responding to negative gravity forces and to movement of the tank to inverted attitude and the other responding to a tank roll.

4. A liquid storage tank which in use assumes different attitudes relative to the earth's surface and which includes outlet and inlet connections, the latter admitting to the tank a liquid-air mixture; including a vent chamber in said tank communicating with the tank exterior; vent tubes communicating at their one ends with different portions of the tank interior and terminating at their opposite ends in said vent chamber, at least one of said tubes communicating at its one end with the normal upper portion of the tank interior; and gravity operated valve means controlling the communication of said one tube with said vent chamber, said valve means including a body providing a first compartment communicating with said vent chamber and a second compartment communicating with the said opposite end of said one tube and with said first compartment, a gravity responsive valve in said first compartment movable to interrupt venting from said first compartment to said vent chamber in response to negative gravity forces and to inversion of the valve body, and a gravity responsive valve in said second compartment movable to interrupt communication between said second compartment and said first compartment in response to a rolling motion of predetermined direction and extent of said body.

5. A liquid storage tank which in use assumes different attitudes relative to the earth's surface and which includes outlet and inlet connections, the latter admitting to the tank a liquid and large amounts of air; including a vent chamber in said tank communicating with the tank exterior; vent tubes reaching at their one ends into opposite ends of the tank in the normal upper portion thereof to vent said upper portion in normal and forward and rearward tilted attitudes of the tank, the opposite ends of said tubes terminating in said vent chamber, a valve body through which said opposite ends of said tubes communicate with said vent chamber, said valve body providing a first compartment communicating with said tubes and a second compartment communicating with the vent chamber and an opening intercommunicating said first and second compartments, a freely rolling ball in said first compartment movable in response to a lateral tilt or roll of the tank of a predetermined extent in one direction to close said opening intercommunicating said first and second compartments, and another ball freely rolling in said second chamber and movable to close said second compartment from communication with said vent chamber under the influence of negative gravity forces and in response to inversion of the tank.

6. A liquid storage tank according to claim 5, characterized in that said first compartment of said valve body is formed with inclined walls to cause said ball therein

to rest normally out of closing relation to said opening
intercommunicating said compartments.
